DESIGN FOR A FOOTBALL GAME TOY

Samuel L. Beder, New York, N. Y.

Application February 21, 1947, Serial No. 137,069

Term of patent 7 years

(Cl. D34—5)

To all whom it may concern:

Be it known that I, Samuel L. Beder, a citizen of the United States, residing at 3150 Rochambeau Avenue, Borough of Bronx, city of New York, county of Bronx, State of New York, have invented a new, original and ornamental Design for a Football Game Toy; of which the following is a specification, reference being had to the accompanying drawings, forming part thereof.

The dial and arrow have been omitted from Figure 1 for convenience of illustration.

I claim:

The ornamental design for a football game toy, substantially as shown and described.

SAMUEL L. BEDER.
